UNITED STATES PATENT OFFICE.

CHARLES J. REBMAN, OF ST. LOUIS, MISSOURI.

BUILDING BLOCK OR BRICK.

Application filed June 5, 1924. Serial No. 718,095.

To all whom it may concern:

Be it known that I, CHARLES J. REBMAN, a citizen of the United States, residing at St. Louis, State of Missouri, have invented 5 certain new and useful Improvements in Building Blocks or Bricks, of which the following is a specification, reference being had to the accompanying drawings.

This invention relates to building blocks 10 or bricks and has for an important object thereof the provision of a block or brick which in a complete wall structure provides at opposite sides of the wall oppositely directed ventilating surfaces.

15 A further object of the invention is to provide a brick of this character in which each brick is of the depth of the wall to be constructed and in which the brick itself is so constructed that the layers of mortar securing opposite sides of the brick in position 20 in the wall are bonded through the brick, thereby insuring a permanent structure.

A still further object of the invention is to provide a device of this character which 25 may be very cheaply and readily produced and which employs in its construction less clay than is ordinarily necessary in the construction of the three ordinary building bricks which it replaces.

30 These and other objects I attain by the construction shown in the accompanying drawings, wherein for the purpose of illustration is shown a preferred embodiment of my invention and wherein:—

35 Figure 1 is a perspective of a section of wall formed of blocks constructed in accordance with my invention;

Figure 2 is a front elevation of the wall partially in section, the section being taken 40 through a bonding opening of the blocks;

Figure 3 is a perspective of one of the blocks removed;

Figure 4 is a further section through the wall taken through the vertical ventilation 45 openings of the blocks.

Referring now more particularly to the drawings, the brick consists of a flat rectangular slab 10 having one end face 11 and the adjacent edges of the two side faces 50 12 glazed. Adjacent this end wall the slab has formed therethrough a vertical opening 13. Adjacent its opposite end the slab has formed therethrough a horizontally extending opening 14. Intermediate these openings a second vertically extending opening

15 is formed the purpose of which will presently appear.

In employing these slabs the slabs are preferably placed in the wall staggered jointed as is usual in the construction of 60 brick and slab walls, mortar being laid between adjacent courses. In this construction mortar is also forced through the opening 15 until it combines with the mortar on the upper face of the course next below and connects the mortar of this course with the mortar on the upper face of the course 65 just laid. This mortar filling the interior of the brick or more particularly the opening 15 thereof provides a solid surface for approximately two-thirds of the length of the brick which is preferably made of a depth equal to the thickness of the wall to be constructed or in ordinary walls about thirteen 70 inches. Since the length of the face of the brick is made the size of the longest measurement of an ordinary building brick, such bricks may be employed, as at 16, in filling in corners and about framing and the like. 75 It is pointed out that due to the construction 80 employed and, as more particularly shown in Figure 4, a continuous vertical ventilating space is provided at the outer face of the wall permitting any moisture which may 85 seep through the outer face of the bricks to pass downwardly to the foundation 17 of the wall so that the wall will not be moist. At the same time in each course a horizontal 90 ventilating space is formed by the combination of the openings 14 of the bricks, 95 providing for heat insulation and rendering a building constructed in this manner cooler in summer and warmer in winter. The construction of the openings 13, 14 and 15 being capable of modification, no particular 100 claim is made to the form of openings provided.

While I have above referred to the use of ordinary brick in the corner construction, I have not illustrated the same and in fact prefer that the filling at corners be accomplished by breaking a block 10 to provide this section. To this end the margin of the central opening 15 disposed next adjacent the glazed wall 11 is spaced from this 105 glazed wall a distance equal to the width of an ordinary brick or slightly less than one-half of the length of the entire block 10. It will be seen that by breaking the brick at the edge of this opening a guide is provided, 110

indicating the proper point of breakage and at the same time the fact that the brick is weakened at this point permits this breakage much more cleanly and evenly than could ordinarily be accomplished. The use of this broken section I have herein illustrated.

I claim:—

A building brick comprising a flat rectangular slab having adjacent one end face a vertical opening therethrough and adjacent the opposite end face a horizontal opening therethrough and intermediate said

openings a second vertical opening, the end face adjacent the first named vertical opening and the adjacent portions of the side 15 faces of the slab being glazed, the side of the second named vertical opening paralleling the glazed end face of the slab, the end walls of said second vertical opening being separated from the side walls by thin, read- 20ily breakable walls.

In testimony whereof I hereunto affix my signature.

CHARLES J. REBMANN.
